UNITED STATES PATENT OFFICE.

EBERHARD FABER, OF NEW YORK, N. Y.

DESIGN FOR A RUBBER ERASER-HEAD FOR LEAD-PENCILS.

56,589.

Specification for Design.

Patented Nov. 16, 1920.

Application filed April 29, 1920. Serial No. 377,720. Term of patent 14 years.

To all whom it may concern:

Be it known that I, EBERHARD FABER, a citizen of the United States, residing at No. 301 West 76th street, county of New York, borough of Manhattan, city and State of New York, have invented a new, original, and ornamental Design for a Rubber Eraser-Head for Lead-Pencils, of which the following is a specification, reference being had to the accompanying drawings, forming part hereof.

The figures are views of the rubber eraser head for lead pencils showing my new design, and Figure 1 is a perspective view, Fig. 2, side view, Fig. 3, front view, Fig. 4, bottom plan view, Fig. 5, top plan view of the rubber eraser head.

I claim—

The ornamental design for a rubber eraser head for lead pencils as shown.

EBERHARD FABER.
